Application May 23, 1956, Serial No. 586,750

Claims priority, application Germany May 28, 1955

8 Claims. (Cl. 208—25)

The present invention relates to the dewaxing of hydrocarbon oils and to apparatus systems suitable therefor. More particularly, it relates to an improved process for the removal of paraffinic components from paraffin-rich oils so that the pourpoint thereof is increased.

Straight-chain organic compounds form crystalline complexes or adducts with urea per se or urea solutions. Branched compounds and cycloaliphatics such as naphthenes combine in a similar manner with thiourea to form adducts. These reactions are useful in the petroleum industry for the removal of paraffin waxes, the adducts being subsequently decomposed for re-use of the adduct forming material after separation from the wax.

For the formation of the urea complex compounds, it is merely necessary to bring the solid urea into contact with straight-chain hydrocarbons. It is advantageous in order to accelerate the formation of adduct to use a solvent for the urea, such as water or a low-molecular weight alcohol. There may also be added an organic liquid which has a good dissolving power for the oil but not for the adduct, so as to dilute the oil and reduce the viscosity thereof.

So that the formation of the adduct does not proceed too smoothly, it is absolutely necessary for the mixture of oil, urea solution and oil solvent to be intensively stirred and mixed. In order to obtain oils having a low pourpoint, the time of contact between the urea solution and oil solution must also be sufficiently long. For the dewaxing of viscous and paraffin-rich oils which are diluted so that they may be handled more easily, very large units with corresponding stirring devices are therefore required. The stirring capacities and stirring energy required, however, add considerably to the overall cost of dewaxing.

It is accordingly an object of the present invention to reduce the size of equipment required for contact of a paraffin-containing oil with a dewaxing agent.

It is a further object of the present invention to provide a process for dewaxing oils wherein the energy requirements are kept to a low value.

In accordance with the present invention, it is proposed that the formation of the adduct be carried out in two stages, namely a first stage in which the mixture of oil, oil solvent and dewaxing agent is stirred intensively but only for a short period of time, and a second stage in which the mixture remains for a longer period of time with slight mixing. In this way, it is possible to make the agitators smaller and considerably to reduce the consumption of power.

If oils which are rich in paraffin are employed there is obtained in connection with the formation of the adduct a thick paste in which the percentage of solids is very high as compared with the percentage of liquid and which can be stirred only with difficulty even though it already contains an oil solvent. The mixing and pumping of the mixture can be facilitated by dilution with additional oil solvent. Since large quantities of solvent are involved, however, considerable heat would be necessary to separate the solvent from the raffinate, i.e., the

2

solution of oil in solvent. Accordingly, whatever energy saving was realized by further dilution of the oil would be lost by the additional heat required to distill off the solvent.

5 In accordance with a modification of the present invention, however, the advantages of additional dilution are realized without increasing the heat requirements for fractionating the raffinate. To this end, a portion of the oil solution which discharges from the separator upon the removal of the solid adduct is returned to the mixer while only the remainder is passed to the evaporator. The total heat consumption in the evaporator station is thereby not increased while the additional power required for the mixing and the transportation of the more strongly diluted mixture is minor compared to the power necessary to move the pulpy less dilute mixture.

20 The return of the oil solution to the mixture can be effected continuously and the increased degree of dilution in the mixture maintained both in the mixing stage and in the rest stage. However, it is also possible to dilute the mixture strongly only in the mixing stage and to separate the excess diluent after leaving the mixing stage and before entering the rest stage, return it again to the mixing stage and thereupon conduct the mixture through the rest stage in the ratio of solid to raffinate solution which corresponds to the quantities of oil used. Since the solid separates almost spontaneously from the raffinate solution, it is sufficient to allow the mixture leaving the mixing stage to settle out for a short time in a settling basin; the solid adduct is then charged with the corresponding quantity of raffinate solution through the zone of rest, while the sufficiently clarified remaining raffinate solution is returned to the mixer. In this way the mixture is maintained in stronger dilution only in the mixer and the corresponding mixer circuit. For 25 this purpose, it is necessary to introduce the desired additional quantity of diluent into the mixer only a single time, namely upon starting-up operations. The stirring and rest capacities can therefore be kept smaller, and the paraffin waxes removed as well as the raffinate will have a homogeneous composition.

30 In the separation of the solids from the liquid phase two possibilities are available in practice. If the liquid phase consisting of oil and solvent is of lower specific gravity than the solid, the latter will settle out in the settling basin and pass at the bottom from said basin into the rest zone while the supernatant raffinate phase is drawn off at the top and returned to the mixer. If on the other hand the liquid phase is heavier, the solid 35 which now separates on the top is conducted by means of an overflow into the rest zone and the raffinate solution is withdrawn from the bottom of the settling basin and conducted to the mixer.

40 In another embodiment of the invention, it may prove 45 advantageous to subdivide the intensive mixing stage into a plurality of agitating stages. The adduct mixture leaving the first agitating stage proceeds through further agitation stages before it enters the rest stage, these further agitation stages each consisting of a mixing apparatus having an intensive agitator followed by a settling basin.

50 In this way, there is obtained an adduct which is of 55 a sandy grit-like form, rapidly settles out and can be filtered considerably more rapidly and scrubbed considerably more intensively and gives better yields of dewaxed oil. The reason for the better adduct formation is the intensive mixing carried out in each agitation stage, which ensures the required fine distribution and intimate mixing of the oil and urea solution. Whereas 60 hydrocarbons of low molecular weight require considerable time to form adducts and would otherwise be combined only during the rest stage, if at all, by subdivision 65 70

of the mixing stage it is ensured that these lower hydrocarbons will be removed during mixing.

This presents still another advantage since the adduct formation is accompanied by the liberation of heat, i.e., is exothermic, and this heat cannot be as readily removed in the rest stage as in the mixers which are already provided with cooling means.

With a multi-mixing stage operation it is also beneficial to recycle a portion of the raffinate to reduce the solids:liquid ratio and thereby reduce the power consumption during transport from the mixer to the rest stage. While the re-cycled raffinate for each stage could come from the final rest stage, this is uneconomical since the oil in this raffinate has already been dewaxed and brought to the desired pourpoint. Accordingly, it is preferable to employ the raffinate from each settling basin to be re-cycled to its own mixer.

The invention will now be described with reference to the accompanying drawing, wherein:

Fig. 1 is a schematic flow sheet of a dewaxing system with a single mixing stage and a single rest stage; and

Fig. 2 is a schematic flow sheet of a dewaxing system with three mixing stages and one rest stage.

Referring now more particularly to Fig. 1, a mixture of 100 parts oil containing about 150 grams of paraffins per liter, 100 parts of urea solution saturated at 70° C. and 100 parts of methylene chloride is allowed to flow into a mixer 11 from lines 12, 13 and 14 and is stirred therein. The mixture passes via lines 15 and 17 and pump 16 into the settling tank 18 and then passes to inclined screw conveyor 19 which constitutes the rest stage. Initially, the material passing to conveyor 19 is almost exclusively adduct. The supernatant raffinate solution in the settling and clarification tank 18 is conducted, also by itself, via the regulating valve 20 and conduit 21 back into the mixer 11 until the desired dilution, i.e., fluidity, has been obtained there. After this point has been reached, sufficient raffinate solution is allowed to enter the screw conveyor 19 from the clarification tank 18 to correspond to the oil introduced, i.e., the difference between the oil constituting the original batch and the adduct. In this way continuous operation is instituted, there being received at the end of the conveyor 19 the quantities of adduct and raffinate solution which are obtained from the oil introduced into the mixer 11. The capacity of the conveyor 19 is greater than that of the mixer 11 so that the dwelling time is greater in the conveyor than in the mixer.

From the conveyor 19 the mixture of adduct and raffinate solution passes to a separator 22. Here the solid adduct is removed and transported by means of a device 23 to the adduct decomposer (not shown) where the adduct forming agent is regenerated. The raffinate solution obtained in the separator 22 is conducted by pump 25 and pipelines 24 and 27 to be processed for the recovery of the solvent.

If the mixture is to be diluted both in the mixing stage and in the rest stage, parts of the raffinate solution are continuously returned into the mixer 11 from the separator 22 by means of pump 25 and line 26; this raffinate solution then passes both through mixer 11 and through the tank 18 to return to the separator 22.

In the operation schematically illustrated in Fig. 2, the mixing stage is subdivided into three agitation stages. A mixture consisting, for instance, of 100 parts of oil containing 120 grams of paraffins per liter, 100 parts of a urea solution saturated at 70° C. and 100 parts of methylene chloride is allowed to flow into the mixer 11 from lines 12, 13 and 14 and there agitated vigorously. The mixture of adduct and raffinate solution passes via line 15, pump 16 and line 17 into the settling tank 18. Through branch 28 a part of the mixture which has previously passed through the turbomixer 29 is returned again to mixer 11, whereby a closed circuit is formed which affords better mixing. The raffinate sep-

arated from the adduct mixture in the settling tank 18 is returned via line 21 to the mixer 11, the quantity being controlled by valve 20. The mixture leaving the settling tank drops into the second mixer 11a and is thoroughly agitated therein as well as by passage through the mixing circuit comprising line 15a, pump 16a, line 17a, turbomixer 29a and line 28a. The portion withdrawn from the mixer circuit passes into the settling tank 18a from whence the separated raffinate is fed via valve 20a and line 21a back to the mixer 11a.

Another thorough mixing is carried out in the third agitating stage, which consists of a mixer 11b and a mixing circuit including conduit 15b, pump 16b, line 17b, turbomixer 29b and line 28b and the settling tank 18b with the raffinate return line 21b and valve 20b. From the settling tank 18b, the adduct mixture passes into the screw conveyor 19, is separated in the separating device 22 from liquid components and discharged via line 23 for further working. The filtrate obtained is removed via line 24 and pump 25 and conducted via line 27 to the evaporator station (not shown) for separation of diluent from the dewaxed oil.

In the event that in the first agitator stage in order to reduce the solid-liquid ratio, there is used a raffinate solution which has already passed through the rest stage, a corresponding portion of this raffinate solution is conducted via conduit 26 into the mixer 11. Of course, it is also possible to force the wash filtrate obtained upon the washing of the adduct in the separator 22 via line 24, pump 25 and line 26 to the mixer 11; the wash filtrate can then, in whole or in part, replace the oil solvent.

This process need not necessarily be carried out in three mixing stages as described here, but the number of stages can be varied as required. The number of circulation systems belonging to one mixing apparatus can also be increased as desired.

As has been pointed out, adduct crystals easily deposit on various places of the apparatus and may form crusts or reduce the cross-section, for instance at the walls of the vessels, at the agitators or the worms. The deposits are avoided if the surfaces of these substances are maintained smooth, and accordingly these surfaces are either highly polished or provided with a suitable protective coating, for instance, of enamel or plastics.

The nature of the dewaxing agent will of course depend upon the chemical constitution of the materials which it is desired to remove from the oil. Similarly, the diluent will have to dissolve the oil but should not dissolve the adduct. By way of example, with an essentially aromatic oil containing a straight-chain paraffinic wax an aqueous solution of urea is suitable as the dewaxing agent in conjunction with the use of methylene chloride as the diluent. The suitability of other materials can readily be determined by reference to solubility tables.

Various changes and modifications can be made without departing from the spirit and scope of the present invention and it is intended that such obvious changes and modifications be embraced by the annexed claims.

What is claimed is:

1. The method of dewaxing an oil which comprises vigorously agitating for a short period of time in a mixing stage, a mixture of a wax-containing oil, a solvent for said oil and an adduct forming agent selected from the group consisting of urea and thiourea to thereby form an insoluble adduct of said wax and said adduct forming agent, permitting said mixture to settle at least partially into a raffinate phase and an adduct phase, withdrawing a portion of said raffinate and recycling same to said mixing stage to thereby increase the fluidity of the mixture therein, conveying the balance of said raffinate together with adduct from said adduct phase to a rest stage, mixing slightly in said rest stage over a longer period of time than in said mixing stage, and separating said adduct from said raffinate.
2. The method defined in claim 1, wherein said wax

comprises essentially straight-chain paraffins and the adduct forming agent comprises a solution of urea.

3. The method defined in claim 1, wherein said wax comprises essentially branched paraffins and the adduct forming agent comprises a solution of thiourea.

4. The method defined in claim 1, wherein said oil solvent is methylene chloride.

5. The method of dewaxing an oil which comprises continuously introducing into a mixing stage, oil, a solvent for said oil and urea, vigorously agitating the contents of said mixing stage to thereby form an insoluble adduct of said urea and said wax and a raffinate of said oil and solvent, continuously withdrawing the contents of said mixing stage after a short dwelling time and permitting at least partial settling, initially passing substantially all of the adduct formed into a rest stage, continuously withdrawing the contents of said rest stage after a comparatively longer dwelling time, initially recycling substantially all of said raffinate to said mixing stage to increase the fluidity, continuing said recycling until the fluidity of the contents withdrawn from said mixing stage reaches a predetermined value, and thereafter continuously adding a portion of said raffinate to the adduct passing through said rest stage while continuously recycling another portion of said raffinate to said mixing stage.

6. The method defined in claim 5, wherein said mixing stage is subdivided into a plurality of agitating stages, the mixture of raffinate and adduct following each agitation being permitted to settle and at least a portion of the settled raffinate being recycled to the respective agitating stage while the balance of the mixture is passed on to the next agitating stage.

7. The method of dewaxing an oil which comprises vigorously agitating in a first mixer stage a mixture of wax containing oil, an oil solvent and urea for a short period of time to form an adduct of urea and wax, permitting said agitated mixture to settle to provide adduct and raffinate, continuously recycling a portion of said raffinate to said first mixer stage while passing another portion of said raffinate together with said adduct to a second mixer stage wherein the raffinate and adduct are slightly agitated over an extended period of time, and thereafter separating the adduct from said raffinate.

8. The method of claim 7, wherein said first mixer stage comprises a plurality of successive agitation stages and a settling stage following each agitation stage, and a portion of the raffinate in each settling stage is continuously recycled to the preceding agitation stage.
